UNITED STATES PATENT OFFICE.

EDWARD J. VON PEIN, OF DAYTON, OHIO, ASSIGNOR TO THE NATIONAL CASH REGISTER COMPANY, OF DAYTON, OHIO, A CORPORATION OF OHIO, (INCORPORATED IN 1906.)

CHECK-ISSUING MECHANISM FOR CASH-REGISTERS.

1,309,829.

Specification of Letters Patent.

Patented July 15, 1919.

Application filed July 16, 1914, Serial No. 851,385. Renewed May 29, 1919. Serial No. 300,776.

To all whom it may concern:

Be it known that I, EDWARD J. VON PEIN, a citizen of the United States, residing at Dayton, in the county of Montgomery and State of Ohio, have invented certain new and useful Improvements in Check-Issuing Mechanism for Cash-Registers, of which I declare the following to be a full, clear, and exact description.

- 10 This invention relates to printing mechanism for check, ticket or receipt issuing machines and the like and more particularly to the means for adjusting attached and previously printed checks, tickets or receipts, etc., in exact position to be severed at the proper dividing line, to receive a printing impression at the proper printing line from a printing device in the machine or for any other purpose.
- 20 The principal object of the present invention is to provide means for adjusting previously printed or made up checks, tickets or receipts comprising a strip, so that the check, ticket or receipt to be issued will be severed at the proper dividing line and so that recording means, positioned in the machine, will record data thereon at the proper line. The use of previously made up checks, receipts or tickets rather than having the machine perform the work of completely making the checks, receipts or tickets from a strip offers several advantages. One of these advantages is that the machine is relieved of the work of making the checks, receipts or tickets. The designs on the checks, receipts or tickets made by machines are usually printed thereon as the checks, receipts or tickets are issued and therefore the ink is not always dry when handled so that ink is often smeared and the hands of the person holding the ticket, check or receipt are soiled. As only the amount, date, etc., are printed on previously made up checks, receipts or tickets the ink quickly dries and the last mentioned objection, which exists when the checks, receipts or tickets are made completely by the machine, is avoided, in addition to providing a better appearing check.

With the ordinary forms of feeding mechanism, such as coöoperating feeding rollers, it has been found that previously made up checks, tickets or receipts are not uniformly fed into severing or printing position. Inaccuracies in the feeding by these forms of

feeding mechanism are due, among other causes, to the difference in the thickness of the ticket, check or receipt strip, and to slight variations in the length of the checks, tickets or receipts which theoretically are of the same uniform size. If there is a slight variation in the strip, the checks, tickets or receipts are severed or printed a little out of the intended lines and if the variation continues through the strip so that the strip is fed a slight distance too far or too little at each movement of the strip, the variations will appear more and more for each succeeding operation and after a while the strip will be severed and printed so far from the proper dividing and printing lines as to spoil the checks, tickets or receipts. In the present invention this objection or defect is overcome, as the device, forming the subject matter of the present invention, is provided with spring pressed fingers for engaging in regularly spaced notches in the strip to move the checks, tickets or receipts in their proper positions to be severed and printed upon.

The present invention in the preferred form of embodiment disclosed herein is shown applied to a cash register for adjusting previously printed receipts in position to be severed and printed upon. It is not intended, however, to limit the invention to the present form of embodiment as it is adapted equally as well for use in ticket or stamp vending machines, perforating machines, time recorders, voting machines and the like without departing from the spirit of the present invention. The receipts issued by the present machine will be so called throughout the present specification but it is to be understood that this term is considered broad enough to include checks, cards, tickets, stamps, time cards, ballots and the like.

With these and incidental objects in view the invention consists of certain novel features of construction and combination of parts the essential elements of which are set forth in appended claims and a preferred form of embodiment of which is hereinafter described with reference to the drawings which accompany and form part of this specification.

Of said drawings:

Figure 1 is a reduced transverse vertical section through a cash register of the type

to which the present invention in the illustrative form of embodiment is shown applied.

Fig. 2 is a detail front view of the type 5 wheels for printing data on the receipts issued by the machine.

Fig. 3 is a right hand side elevation of the printer with the improvements assembled in position and with portions of the 10 printer and machine frames broken away and omitted to expose the driving and printing mechanism more clearly to view.

Fig. 4 is an enlarged detail front view of the improvement for adjusting the receipts in their exact severing and printing 15 positions.

Fig. 5 shows receipts of an illustrative form adapted to be adjusted in proper position by the device shown in Figs. 3 and 20 4. The lower receipt shows the data printed thereon by the type wheels shown in Fig. 2, and also the design previously printed thereon.

The present invention for illustrative purposes, has been shown in the present application applied to a printing mechanism of the type disclosed in the present applicant's Patent No. 1,198,492, dated September 19, 1916, and based upon an application 25 filed November 15, 1913. The printing mechanism in the present application as well as in the above mentioned patent is shown attached to a type of cash register well known on the market and shown and described in United States Letters Patent No. 35 580,378, granted April 13, 1897, to J. P. Cleal and F. A. Reinhard.

As the type of machine to which the present improvement is shown applied is fully 40 described and illustrated in the patent just mentioned, it will be unnecessary to describe the same in detail herein, but for the purposes of illustration a brief description of the principal mechanisms of a machine of 45 that type will be given. The operating mechanism is shown in Fig. 3 and comprises an operating handle 10 rigidly connected to a pinion 11 meshing with a large intermediate gear 12. This intermediate gear 12 50 meshes with a gear 13 which in turn meshes with a gear 14 which is rigidly mounted on the shaft 15 and indicated in the drawings by dotted circles. This gearing is so proportioned that upon every two complete rotations of the operating handle the shaft 55 15 is given one complete rotation.

As shown in Fig. 1 a plurality of keys 16 act to control differentially the adjustment of an operating member 17. The keys 16 60 are arranged in banks and the number of banks provided depends on the registering capacity desired of the machine. It is understood, of course, that there is an operating member 17 for each bank of keys 16 and 65 the members 17 are actuated differentially

to adjust the intermediate gears 18 and through the medium of these gears actuate the indicating mechanism 19 and the totalizer mechanism (not shown) in the manner set forth in the aforesaid Cleal and Reinhard patent. The operating members 17 70 carry pins 21, there being one pin on each member, and these pins project into cam slots 22 formed in arms 23, each of which is fast to the inner end of one of a series of nested sleeves 24 which project to the right and through suitable operating connections (not shown) adjust differentially a series of amount type wheels 25 (Fig. 2) to a position appropriate to the adjustment of the operating members 17 under the control of the 80 keys 16. An initial type wheel 26 and a special type wheel 27 are positioned differentially under the control of initial keys and special keys (not shown) in the same manner as the amount type wheels are adjusted.

The operating mechanism for giving the operating movement to the members 17 is 85 fully illustrated in Fig. 1 and as it forms no part of the present invention and is fully described and illustrated in the before mentioned Cleal and Reinhard patent no description of the same will be given herein.

In addition to the type wheels just described, type wheels 28 (Fig. 2) for printing the consecutive numbers of the transactions on the detail strip 30 (Fig. 3) and the receipts 31 (Fig. 5) comprising the receipt strip 32 (Fig. 3) are provided. Type 90 wheels 29 for printing the date are provided 100 also. The date wheels 29 are adjusted by turn buttons which are not shown in the drawings but contained in the cap 33 (Fig. 3) and the means for operating the consecutive number wheels 28 is not shown as any 105 desired means such as that disclosed in the before mentioned patent of the present applicant, can be employed. The impression means for carrying the detail strip 30 against the type wheels and the feeding 110 means for this strip are not shown herein as they form no part of the present invention.

An inking ribbon 36, which may be fed in any desired manner from a supply roll 115 37 about the type wheels and onto the storage roll 38, is employed to supply the ink for making the impressions from the type wheels on the detail strip and the receipts.

The impressions taken from the type wheels 120 upon the receipts 31 (Fig. 5) are made by a platen 40 carried by a frame 41 pivoted to a pair of arms 42 fast on a shaft 43. The right hand side arm 42 bears a roller (not shown) which projects into a cam groove 125 (not shown) formed in a disk 45 (Fig. 4) fast on the shaft 46. The cam groove in the disk 45 is so constructed that during the operation of the machine and after the receipt to be printed has been adjusted in its 130

proper position the platen is raised once to take an impression from the type carriers on the receipt. The platen frame 41 (Fig. 3) is guided in its operating movements by the engagement of a stud 39 mounted on the frame 41 in the slot formed in a stationary guide plate 44. The shaft 46 is given one complete rotation at each operation of the machine through the train of gears shown in Figs. 3 and 4. One of these gears 47 is fast on the shaft 46 and meshes with a gear 48 fast on a shaft 49. The gear 48 in turn meshes with a gear 50 and the latter gear meshes with a gear 51 fast on a shaft 52. The last mentioned gear meshes with a gear 53 which is fast on the shaft 15 and indicated by dotted circles in Fig. 3. With this train of gears one complete rotation of the shaft 15 at each operation of the machine is imparted to the shaft 46 and the shafts carrying the intermediate gearing.

The receipt strip 32 is fed from a supply roll (not shown) through a guide 55 between coöperating feed rollers 56 (Fig. 3) and 57 (Figs. 3 and 4), through a guide 58 and then through a shearing slot in a stationary knife 59 and under the type wheels. Peripheral flanges 60 on the feeding roller 56 rigidly mounted on the shaft 49, are so constructed that they coöperate with the feeding roller 57 to feed a receipt at each operation slightly past printing position. A plate 61 of a pivoted yoke 62 is held in engagement with the receipt strip by a spring 63 to hold the receipt strip against the chute 55 and thereby keep the strip taut during the feeding of the strip by the feeding rollers. The back of the chute is slidably mounted near its upper end on screws 100 and at its lower end on studs 99 which project through slots formed in lugs 101. A spring 63 which is fastened to a lug 102 on the back of the chute retains the back in elevated position. When the back is lowered by the finger piece 103 on the back a projection 104 on the latter engages a projection 105 on the yoke 62 to rock the latter rearwardly and thereby permit the receipt strip to be easily started through the chute, when the strip is attached to the machine.

Before the platen 40 is operated to print upon a receipt, the receipt, which has been moved slightly past printing position by the feeding rollers, is moved slightly rearward into its exact printing position by the device forming the subject matter of the present invention and now to be described.

Rigidly mounted on the shaft 65 (Figs. 3 and 4) supported by the printer frame is a yoked frame 66 from the forwardly extending side arms 67 of which is pivotally swung by pins 64 a frame comprising an arm 68 and a lever 69 connected by and integral with a cross bar 70. Spring pressed plungers or finger pieces 71 are slidably mounted on the

lower ends of the lever 69 and arm 68, the finger pieces being provided with slots 72 through which guide pins 73 carried by lever 69 and arm 68, project. Upwardly extending projections or pins 74 of the finger pieces 71 project through apertured lugs 75 (Fig. 4) and springs 76 (Figs. 3 and 4) coiled about the projections 74 and compressed between the lugs 75 and the finger pieces normally serve to retain the upper ends of the slots 72 in engagement with the pin 73. Downwardly extending fingers 79 (best shown in Fig. 3) are adapted to project through slots 78 (best shown in Fig. 4) formed in the lower forward end of the front plate of the guide 55 and through notches 77 (Fig. 5) formed in the sides of the receipt strip between the receipts 31 at the cutting line. The fingers 79, however, are normally held in the elevated position shown in Fig. 3 free of the receipt strip, to permit the feeding of the receipt strip by the feeding rollers 56 and 57. An upwardly extending arm 80 integral with the left hand side of the yoked frame 66 carries at its upper end a roller 81 projecting into a cam groove 82 formed in the face of a disk 83 rigidly mounted on the shaft 52. A pitman 84 at its lower end is connected to the upwardly extending arm of the lever 69 by a screw 86 having an eccentric portion 85 which passes through the pitman 84. A nut 110 is employed to fasten the screw in adjusted position, the screw being used to control the extent of rocking movement of the frame 68 so that the proper adjustment of the receipt can always be obtained if a change in the size of the receipts is made. The pitman 84 at its upper end is forked over the shaft 52 and carries a roller 87 which projects into a cam groove 88 formed in a disk 89 also fast on shaft 52.

The operation of this device just described is as follows: The cam groove 88 is so designed that during the rotation of the shaft 52 and after the receipt strip has been fed forwardly by the feeding rollers 56 and 57 the pitman 84 is drawn in the direction of its length toward the shaft 52 thereby rocking the frame comprising the lever 69, arm 68 and cross bar 70 forwardly about its pivotal center to move the fingers 79 slightly past and over the notches 77 between the first and second receipt in the receipt strip. Then near the end of the operation of the machine but before the printing impression has been made by the platen 40 the cam groove 82 rocks the frame 66 counter clockwise to lower the fingers 79 into engagement with the sides of the upper face of the receipt to be printed upon, the springs 76 being slightly compressed at this time by this engagement. The cam 88 then operates the pitman 84 to swing the frame, comprising the levers 69 and 68 and the cross bar 130

70 counter clockwise. During this movement of the last mentioned frame the fingers 79 slide into coöperative relation with the notches 77 whereupon the springs 76 move 5 the finger pieces 71 downwardly to carry the fingers 79 into engagement with the notches so that during the continued movement of the frame the fingers draw the first receipt slightly rearwardly. In this position of the 10 receipt the receipt will be severed, on the line 91, from the strip (Fig. 5) by the co-operation of a movable knife 92 with the stationary knife 59 and the receipt will also be in position to receive a printed impression 15 at the proper line. Immediately after the check has been printed upon it is severed from the check strip and then the pitman 84 is moved back to normal position by its cam to raise the fingers 79 out of 20 engagement with the receipt strip and into the position shown in Fig. 3.

From the above description it can be seen that if the check is fed slightly too far by the feeding rolls the fingers 79, being moved 25 forwardly slightly past the position to which the notches 77 of the check strip should uniformly be moved by the feeding rollers will engage in the notches to carry the receipt into proper position to be severed and 30 printed. As the feeding rollers always feed the receipts past printing and severing position the receipts will be adjusted to this printing and severing position by the fingers 79 even if the feeding rollers feed the 35 receipts forwardly to an intermediate position, that is between severing and printing position and the position to which the rollers are intended to feed the receipts.

The movable knife 92, (Fig. 3) is carried 40 by a frame 93 supported by the forward ends of arms 94 loosely mounted at their rear ends 93. The right hand side arm 94 carries a roller 95 which projects into a cam groove 96 formed in a disk 97 rigidly mounted 45 on the shaft 46. The cam groove 96 is so shaped that the movable knife 92 will be raised immediately after the platen 40 has been operated and while the receipt is retained in its correct severing and printing 50 position by the finger pieces 71 to sever the check from the strip on the line 91 (Fig. 5).

As the printing mechanism and the cash register to which the present invention is applied in the illustrated form disclosed 55 herein is well known in the art and disclosed in the above mentioned application and patent and as the device of the present invention is simple and has been fully described above it is thought unnecessary to give a 60 résumé of the complete operation of the machine, the foregoing description being considered complete in itself for a perfect understanding of the present invention.

While the form of mechanism here shown 65 and described, is admirably adapted to fulfil

the objects primarily stated, it is to be understood that it is not intended to confine the invention to the one form of embodiment herein disclosed, for it is susceptible of embodiment in various forms all coming within the scope of the claims which follow.

What is claimed is:—

1. In a machine of the class described the combination with an arm having oscillating and bodily movements for coöperating with 75 openings in a paper strip to adjust the strip in proper position, of means for bodily moving the arm into coöperative relation with the openings, and means for oscillating the arm to adjust the strip in proper position.

2. In a machine of the class described the combination with a device capable of having two kinds of movements for coöperating with openings in a paper strip to adjust the 85 strip in proper position, of a cam for giving said device movement of one kind to move it into coöperative relation with said openings, and a cam for giving said device the other kind of movement to adjust the strip 90 in proper position.

3. In a machine of the class described the combination with an oscillatory and bodily movable device having spring pressed fingers for coöperating with openings in a receipt strip, of operating means for bodily moving said device to move said fingers into operative relation with said openings, and for oscillating said device to adjust the first receipt in proper position.

4. In a machine of the class described the combination with a pivoted member having spring pressed fingers for coöperating with openings in a receipt strip, of a pivoted supporting frame on which said member is pivoted, and operating means for rocking said supporting frame to carry said fingers into coöperative relation with said openings, and rocking said member so that the fingers adjust the receipts in the receipt strip in 110 proper position.

5. In a machine of the class described the combination with a pivoted member having spring pressed fingers for coöperating with openings in a receipt strip, of a pivoted supporting frame on which said member is pivoted, a cam for rocking said supporting frame to carry said fingers into coöperative relation with the openings, and a cam for rocking said member so that the fingers adjust the receipts in proper position.

6. In a machine of the class described, the combination of means for feeding a perforated or recessed receipt strip an approximately invariable distance in one direction 125 past a definite position, and means for coöperating with openings in said strip to move the strip in the reverse direction only and thereby adjust the receipts in said definite position.

7. In a machine of the class described the combination with a pivoted member having spring pressed fingers for coöperating with openings in a receipt strip, of a pivoted supporting frame on which said member is pivoted, operating means for rocking said supporting frame to carry said fingers into co-operative relation with said openings, and rocking said member so that the fingers adjust the receipts in the receipt strip in proper position, and adjustable connections intermediate said member and said frame. 10
8. In a machine of the class described, the combination with adjusting fingers to engage openings in a paper strip but normally out of contact with the strip, of a device having a compound movement and carrying said fingers, and means for imparting compound movement to said device first to move said fingers into contact with the strip and then to engage the fingers with the openings and adjust the strip. 15
9. In a machine of the class described, the combination with means for feeding a receipt strip in one direction, and means for coöperating with openings in said strip to move it in the reverse direction for adjusting the same. 20
10. In a machine of the class described, means for pulling strip material having openings or recesses therein, and means co-operating with the openings in said strips to push it in the reverse direction for adjusting the same. 25
11. In a machine of the class described, feed rollers for feeding in a given direction strip material having openings or recesses therein, and oscillating means coöperating with the openings in said strip for adjusting the same in the reverse direction. 30
12. In a machine of the class described, feed rollers for feeding in a given direction strip material having openings or recesses therein, and oscillating arms coöperating with the openings or recesses in said strip for adjusting the same in the reverse direction. 45
13. In a machine of the class described, feed rollers for feeding in one direction strip material having openings or recesses therein, and oscillating arms having spring pressed fingers coöperating with the openings or recesses in said strip for adjusting the same in the reverse direction. 50
14. In a machine of the class described, feed rollers for feeding in one direction strip material having openings or recesses therein, oscillating arms, means for moving said arms into coöperation with the openings in said strip, and means for oscillating said arms to adjust the strip in the reverse direction to that in which it is fed by the feed rollers. 55
15. In a machine of the class described, feed rollers for feeding in a given direction strip material having openings or recesses therein, means for adjusting the strip in the reverse direction, a cam for moving said means into coöperation with the openings in the strip, and a cam for actuating said means for adjusting the said strip. 60
16. In a machine of the class described, feed rollers for feeding in one direction a perforated or recessed strip, oscillating arms, a cam for moving said arms into coöperation with the openings in said strip, and a cam for oscillating said arms to adjust the strip in the reverse direction to that in which it is fed by the feed rollers. 65
17. In a machine of the class described, feed rollers for feeding in one direction a strip having holes or recesses therein, oscillating arms having spring pressed fingers, a cam for moving the said fingers into coöperation with the openings in said strip, and a cam for oscillating said arms to adjust the strip in the reverse direction to that in which it was fed by the feed rollers. 70

In testimony whereof I affix my signature in the presence of two witnesses.

EDWARD J. VON PEIN.

Witnesses:

F. E. HAMILTON,
J. B. RICKETTS.

It is hereby certified that in Letters Patent No. 1,309,829, granted July 15, 1919, upon the application of Edward J. Von Pein, of Dayton, Ohio, for an improvement in "Check-Issuing Mechanism for Cash-Registers," errors appear in the printed specification requiring correction as follows: Page 4, line 123, claim 6, for the word "of" read *with*; same page and claim, lines 123-124, strike out the words "perforated or recessed"; page 5, line 24, claim 9, for the word "with" read *of*; same page, line, and claim, after the article "a" insert the words *perforated or recessed*; and that the said Letters Patent should be read with these corrections therein that the same may conform to the record of the case in the Patent Office.

Signed and sealed this 7th day of October, A. D., 1919.

[SEAL.]

M. H. COULSTON,

Acting Commissioner of Patents.
